WALL PLANTER

William H. Robinson, San Clemente, Calif.

Application December 6, 1952, Serial No. 22,582

Term of patent 14 years

(Cl. D35—3)

To all whom it may concern:

Be it known that I, William H. Robinson, a citizen of the United States and resident of San Clemente, county of Orange, State of California, have invented a new, original, and ornamental Design for a Wall Planter, of which the following is a specification, reference being had to the accompanying drawing, forming a part hereof, in which:

Fig. 1 is a front view of a wall planter showing my new design;

Fig. 2 is a top view;

Fig. 3 is a bottom view;

Fig. 4 is a front view; and

Fig. 5 is a vertical transverse section.

The dominant features of my design reside in the portions shown in full lines.

I claim:

The ornamental design for a wall planter, substantially as shown and described.

WILLIAM H. ROBINSON.
